CLAIM

The ornamental design for a keyboard, as shown and described.

DESCRIPTION

FIG. 1 is a front perspective view of a first embodiment of a keyboard showing our new design;

FIG. 2 is a front view thereof;

FIG. 3 is a back view thereof;

FIG. 4 is a top view thereof;

FIG. 5 is a bottom view thereof;

FIG. 6 is a right view thereof;

FIG. 7 is a left view thereof;

FIG. 8 is a front perspective view of a second embodiment of a keyboard showing our new design;

FIG. 9 is a front view thereof;

FIG. 10 is a back view thereof;

FIG. 11 is a top view thereof;

FIG. 12 is a bottom view thereof;

FIG. 13 is a right view thereof; and,

FIG. 14 is a left view thereof.

The broken lines in drawings show portions of the keyboard that form no part of the claimed design.

1 Claim, 10 Drawing Sheets
